GAS BURNER

Best Pratt, Chicago, Ill., assignor to Certified Gas Equipment Company, Chicago, Ill., a corporation of Illinois

Application December 18, 1939, Serial No. 309,869

5 Claims. (Cl. 158—104)

The present invention relates to gas range burners.

The principal objects of the invention are to provide burner devices for use with a gas range and which devices are economical in manufacture, capable of ready assembly, and provide a highly efficient flame with economical gas consumption.

Other objects and advantages of the invention will be apparent from the following specification and attached drawings wherein

Figure 1 is a view of a burner of the present invention, the view showing the burner in diametrical front to rear vertical section and mounted on a mixing tube.

Figure 2 is a top plan view of a burner base plate.

Figure 3 is a bottom plan view of a base plate.

Figure 4 is a side elevation of the base plate of Figures 2 and 3.

Figure 5 is a developed view of a base plate taken on the line 5—5 of Figure 2.

Figure 6 is a bottom view of the burner body of Figure 1.

Figure 7 is a radial section of a burner body and base plate taken on a line corresponding to the line 7—7 of Figure 2.

Figure 8 is a view showing a burner device of large capacity in front to rear diametrical section, the view also showing a portion of a mixing tube in longitudinal vertical section.

Figure 9 is a radial sectional view of the burner body and base plate of Figure 8, the view being taken on a line corresponding to the line 9—9 of Figure 12.

Figure 10 is a vertical sectional view on the line 10—10 of Figure 8.

Figure 11 is a developed section on the line 11—11 of Figure 12.

Figure 12 is a top plan view of a modified form of base plate.

Figure 13 is a bottom plan view of the base plate of Figure 12.

Figure 14 is a bottom view of the burner of Figure 8.

Figure 15 is a side elevation of the base plate of Figure 12.

Figure 16 is a bottom plan view of a modified form of burner device.

Figure 17 is a vertical sectional view on the line 17—17 of Figure 16.

Figure 18 is a developed sectional view on the line 18—18 of Figure 16.

Figure 19 is a bottom plan view of a modified form of burner device.

Figure 20 is a vertical sectional view on the line 20—20 of Figure 19 and

Figure 21 is a developed sectional view on the line 21—21 of Figure 19.

Figures 1 to 7 illustrate a main burner 19 of average capacity assembled upon a mixing tube 15 with a simmer burner 18, while Figures 8 to 15 illustrate a main burner 17 of large capacity assembled upon a mixing tube 15 with a simmer burner 18.

Referring to Figure 1, it will be noted that the burner 19 includes a base plate 170 and a burner body 200. The base plate 170 is of annular form as shown by the Figure 2 top plan view thereof.

15 A hollow inlet boss projects downwardly from one side of base plate 170 and has an inlet 202 formed therein which is of the same outline as the outlet 162 of the mixing tube to which it is fitted. The mixing tube may be of the type disclosed in my divisional application, Serial No. 541,162, filed June 20, 1944, for "Gas range structures," which is a division of the present application. As best

20 shown in Figure 5, which is a development of the base plate 170 taken on the line 5—5 of Figure 2, the inlet portion of the boss is in the form of a short vertical sleeve which opens into portions diverging circumferentially of the base plate, with the lower walls 204 of the diverging portions being curved in vertical section and inclining upwardly to points on a line approximately half-way about the circumference of the base plate as also shown in Figure 2. From this point onward, the upper and interior surface of the base plate is substantially flush with its bounding edges.

25 Base plate 170 is supported by the box-like projection 201 which seats upon a mixing tube with its inlet 202 in alignment with the outlet 162 of the mixing tube. Threaded sockets 206 in the boss-like projection 201 will then be in alignment with the apertures in the mixing tube.

The burner body 200 is also of annular form to define a central aperture 19a. The inner wall 208 is outwardly inclined but substantially straight to a point substantially midway of the height of the burner body and thence curves outwardly as indicated at 209 to join the outer wall of the burner body. The outer wall is curved inwardly as indicated at 210 and thence extends upwardly, slightly inclined inwardly to the vertical, as indicated at 211. In other words, the outer wall of the burner body, in radial section, comprises a rounded abutment surmounted by a substantially straight and inwardly inclined face 212. The angle of inclination of face 212 from the vertical

30 is approximately eleven and one-half degrees.

35

40

45

50

55

Jet apertures 213 are provided in the face 212 on lines at right angles to the face 212 so that their axes will be slightly inclined upwardly and outwardly. The provision of the lower rounded portion 210 in the outer wall of the burner body provides a projection beneath the jet apertures which causes secondary air to flow upwardly and inwardly toward the mouths of the burner jet ports, giving a more efficient flame. Also, the provision of this outwardly curved wall provides a widened gas passage within the burner beneath the line of the jet ports so that an unrestricted flow of gas will be provided within the circular burner body. The provision of the deep inlet boss with inclined lower walls also gives improved gas and primary air distribution.

The burner body 200 and base plate 170 are joined by screws passing through apertured and suitably threaded ears 210a and 170a as best shown in Figure 7.

The burner device of Figures 1 to 7 may be described as of average size.

The simmer burner 18 illustrated in Figure 1 is similar to that shown in Figure 8 and is described in connection with the latter figure.

Figure 8 illustrates a large capacity burner 17 comprising a burner body 235 and a base plate 236.

The burner base plate 236 illustrated in Figures 8 to 15 is identical in construction with that illustrated and described in connection with Figures 1 to 7 except that it is of larger diameter, being designed to support the burner body 235 of larger capacity. Also, the lower wall 204a of the diverging inlet portion of the base plate 236 is uncurved as shown in Figure 11.

The burner body 235 is somewhat wider in radial section than the burner body 200 and its inner wall 237 is rounded outwardly from a point adjacent its lower edge, the top portion of the inner wall in effect forming the top wall 238 of the burner body. The outer wall of the burner body includes a substantially vertical slightly inwardly inclined lower portion 242 which terminates at a rounded shoulder or ledge 243 which is inclined very slightly upwardly. Above ledge 243 a vertical face 244 is provided having its upper portion rounded to join the top wall 238. The upper vertical wall 244 is inclined inwardly at an angle of approximately eleven and one-half degrees from the vertical. Jet ports 245 extend through the wall 244 at substantially a right angle with respect thereto and immediately above the ledge 243.

The provision of the slightly inwardly inclined lower wall portion 242 together with the rounded and upwardly inclined ledge 243 insures that a stream of upwardly and inwardly moving secondary air will be supplied to the jet ports.

It will be observed that in both the Figure 1 and Figure 8 burners the burner jet ports are protected from spilled or overflowing food due to the fact that they are positioned immediately above downwardly inclined shoulders. In other words, any substance spilling upon the burner will flow downwardly off the shoulders rather than into the jet ports. Also, the provision of the rounded inner walls insures that food dropping upon the same will flow downwardly. Since the simmer burner jets 218 are spaced inwardly from the inner walls of the main burners, as herein-after described, these latter jets will not be affected by dropping of any substance upon the burners.

The jet ports 213 and 245 of the respective main

burners are closely spaced entirely around the burners and are of relatively small diameter so that a continuous ring of flame will be directed upwardly.

5 Each simmer burner 18 includes a sleeve portion 215 which is adapted to extend down through the simmer burner chamber 166 with its lower portion beneath the lower wall of the chamber to receive a nut 216. The position of the sleeve 215 vertically in the chamber 166 will be determined by the contact of the lower and outer edge of a return bent flange 217 on the upper end of the sleeve. The bight of the flange 217 is provided with jet apertures 218 inclined very slightly inwardly from the vertical, preferably at an angle of approximately twenty degrees.

It will be noted that while the extreme upper surface of the simmer burner 18 is substantially flush with the lower surface of the main burner 20 base plate, a space is provided between the inner edge 171 of the base plate wall and the opposed curved surface of the simmer burner. This will permit an entirely adequate supply of secondary air to reach the simmer burner, while the fact 25 that the simmer burner flame will be within and above the lower portion of the main burner will prevent such flame from being extinguished by drafts.

The downwardly projecting portion 219 of the 30 burner flange is provided with a jetted nipple 220 so positioned as to face the pilot burner combustion tube 25 associated with that burner. Hence, when gas is supplied to the simmer burner, some gas will flow through the nipple 220 into the 35 combustion tube and will there be ignited to cause a flame to flow from that tube to ignite the gas issuing from the jet ports 218 of the simmer burner. In order that the main burner may be ignited from the simmer burner, the base plates 170 and 236 are radially slotted as indicated at 221 40 at a point preferably diametrically opposite the inlets 202 and 202a of the main burner, as best shown in Figures 2 and 12. Hence, when the main burner is supplied with gas, gas will issue 45 from the slot 221 toward the simmer burner to be ignited and a flame will then move up along and in a lateral recess on the outer surface of the main burner formed by a recess 222 in the base plate adjacent the outer end of the slot 221 and a recess formed in the outer wall of the body of the main burner. The inner shoulder of the base plate recess is rounded as shown in Figure 1 to 50 permit the gas to readily move upwardly around the same.

55 In the Figure 1 burner body 200, the igniting recess 222a has straight or vertical side walls 223 and an inner wall 225 which is a continuation of the upper wall 212. Thus, in the Figure 1 burner body 200 the igniting recess extends substantially directly upwardly to the jet ports 213. In the Figure 8 burner body 235, the recess 222b has radial side walls 228 and an outwardly inclined top wall 229 which opens to the outer wall 242 of the burner body at a point below the ledge 243. In other words, the recess is outwardly and upwardly facing. Both base plates 170 and 236 are provided with shoulders 230 on their bottom faces arranged at an angle to the slots 221 to prevent the plates from spreading at the slots before 65 they are applied to the burner body.

Figures 16 to 21 show one piece burner devices, that is, burner devices wherein the base plate and burner bodies are formed integrally. Figure 16 shows a large capacity burner device 250 of an annular form and including a bottom wall 251 which

is adapted to be horizontally arranged and extends for substantially 180 degrees about the burner device as best shown in Figure 16 and then is inclined downwardly as indicated at 252 to an inlet boss portion 253. The inlet aperture 254 of the inlet boss is substantially segmental in top plan and is adapted to be mounted upon mixing tubes of the types heretofore described, but having the aligned outlet apertures of a form to fit the inlet aperture 254 of the burner device. As best indicated in Figure 18, a stream of gas moving upwardly through the inlet aperture 254 will be divided to flow upwardly above and along the inclined bottom wall portion 252 and thence entirely about the burner. As illustrated in Figure 17, the inlet portion of the burner device, that is, the portion directly above the inlet 254, is of much greater cross section than the opposite portion of the burner above the flat lower wall 251. This will, of course, insure that the flow of incoming gas will be in no way restricted and that a uniform supply of gas will be furnished throughout the annular burners.

The outer wall 256 of the burner device is substantially vertical but slightly inwardly inclined and terminates in a rounded and upwardly inclined ledge 257 merging with an upper vertical wall 258 inclined inwardly from the vertical at an angle of approximately eleven and one-half degrees. The inner wall 260 is rounded outwardly as best shown at the left hand portion of Figure 17 and merges with a downwardly inclined top wall 261. As best shown at the right hand portion of Figure 17, a vertically extending lower inner wall 262 is provided opposite the enlarged portion of the burner to connect with the downwardly inclined lower walls 252.

Jet ports 263 are provided in the upper outer wall portion 258, these ports being arranged substantially at right angles to that wall so as to be inclined slightly upwardly.

In order that a highly efficient distribution of gas may be obtained throughout the entire circumference of the burner, a depending baffle or partition 265 extends about the burner above the inlet 254 and the inclined bottom walls 252. The baffle projects downwardly from the top wall 261 substantially midway between the lower portion of the inner wall 260 and the lower outer wall portion 256. However, since the upper outer wall portion 258 is spaced inwardly from the lower outer wall portion 256, a restricted passage 266 will be provided between the outer face of the baffle wall 265 and the jet apertures 263.

The central portion of the baffle wall 265, that is the portion above the inlet aperture 254, has its lower edge horizontal but immediately at each edge of the aperture the lower edge of wall 265 is inclined upwardly, as indicated in Figure 18 so that it extends substantially parallel with the inclined lower wall 252.

The provision of the baffle 265 insures that a proper proportion of the incoming gas and air will be excluded from the jet ports 263 in the semi-circular portion of the burner in which the inlet 254 is provided and that at least half the incoming gas will flow to the inward side of baffle 265 toward the jet ports in the remaining semi-circle of the burner, i. e., the jet ports above the flat bottom wall 251 and beyond the far edges of the baffle 265.

The burner of Figures 16 is intended to be preferably ignited from a simmer burner such as 18 illustrated in Figures 1 and 8. For this purpose, burner 250 is provided with a recess 270 prefer-

ably arranged diametrically opposite the inlet 254. The side walls 271 of the recess are vertical and the inner wall is also substantially vertical but rounds inwardly as shown at 272 to a point substantially midway of the thickness of the annulus. The lower edge of the inner wall 260 may also be rounded as shown at 273 at its lower edge.

A slot 275 is cut through the lower wall of the burner as indicated in Figures 16 and 17 centrally of the lower portion of the recess 270. As a result of this, gas issuing through the slot 275 will be ignited from a simmer burner or the like and the flame will thus extend upwardly along the inner wall 270 of the recess to ignite gas simultaneously issuing through the jet ports 263.

The provision of the rounded under edge 272 of recess 270 insures that a flame will readily travel outwardly to the recess 270. The lower wall 251 of the burner preferably projects upwardly into the burner chamber or passage adjacent the recess 270, the upper surface of the major portion of the lower wall 251 being indicated in Figure 17 by the numeral 276 while the upper wall of the recessed portion is indicated by the numeral 277. This formation both strengthens the burner adjacent the slot 275 and also somewhat restricts the flow of gas through the slot.

The burner device illustrated in Figures 19 to 21, of average capacity, is substantially identical with that shown in Figures 16 to 18 except that the inner wall 260a of the Figure 19 burner device is substantially straight to a point opposite the jet ports 263a, this wall then curving outwardly to form a top wall 261a. Also the outer wall 270a is rounded inwardly from its lower edge to a point immediately below the jet ports 263a, being curved upwardly immediately below these ports as indicated at 257a.

In the Figure 19 burner the baffle plate 265a extends downwardly from the interior of the upper inclined portion 258a of the outer wall and immediately below the jet ports 263a so that a chamber 280 is formed beneath the inwardly curving outer wall 256a and the outer surface of the baffle 265a and through which gas may flow to the jet ports in the semi-circular portion of the burner distant from the inlet aperture 254a and above the horizontal portion 252a of the bottom wall of the burner. From Figure 21 it will be observed that the lower edge of the inclined portions of baffle 265a diverges slightly from the lower wall portion 252a, giving the desired proportioning of the inflow of gas in a burner of average capacity. Also, the central portion of the baffle is quite close to the inlet aperture 254a.

The igniting recess 278 of the Figure 19 burner has its inner wall 272a inclined at about the same angle of inclination to the vertical as the upper portion 258a of the outer wall of the burner.

The burners described in Figures 16 to 21 have the same advantages as to flame qualities, secondary air supply, and the protection of the jets from substances spilled upon the burner as have been set forth above in connection with the burners illustrated in Figures 1 to 15.

It will be understood that all of the burners described herein may be used with mixing tubes of various types.

Subject matter disclosed but not claimed herein may be claimed in my above mentioned divisional application, Serial No. 541,162, filed June 20, 1944, for "Gas range structures."

The terminology employed in the specification is for the purpose of description and not of limi-

tation, the scope of the invention being defined in the following claims.

I claim:

1. In combination, a burner of annular form and including an annular gas chamber formed by a bottom wall and inner and outer walls projecting upwardly therefrom, said outer wall being provided with a circumferential series of jet ports, a vertical slot through said bottom wall so that gas may flow therethrough from the gas chamber to atmosphere, a recess in said outer wall extending from the slot to a point substantially immediately below the jet ports, and means to ignite gas issuing from the slot so that a flame will extend upwardly in the recess to ignite gas issuing from the jet ports.

2. A gas range burner of annular form including, in radial section, top, bottom and side walls, a side wall of said burner being provided with a circumferential series of jet ports, a gas inlet port opening through the bottom wall of the burner, and a baffle plate projecting downwardly from said top wall intermediate the width of said wall, said plate being longitudinally arcuate to extend partially about the circumference of the burner and having its lower edge disposed below the series of jet ports and facing the gas inlet port to divide the stream of inflowing gas, said baffle plate being of increasing depth from each end to an intermediate portion and said intermediate portion of greatest depth being opposite the gas inlet port.

3. The structure defined in claim 1 wherein said gas igniting means comprises a simmer burner positioned below and centrally of said annular burner.

4. A gas range burner of annular form including, in radial section, a bottom wall and upper

walls so positioned with relation to said bottom wall as to define with said bottom wall an enclosed annular gas passage, one of said upper walls being provided with a circumferential series of jet ports opening from the gas passage, a gas inlet port opening through said bottom wall, and a vertically disposed baffle plate projecting downwardly from one of said upper walls, said baffle plate being longitudinally arcuate to extend partially about the circumference of the burner and having its lower edge disposed below the series of jet ports and facing the gas inlet port to divide the stream of inflowing gas and being of increasing depth from each end thereof to an intermediate portion and said intermediate portion of greatest depth being above the gas inlet port.

5. A gas range burner of annular form including, in radial section, a bottom wall, inner and outer side walls and a top wall, an intermediate portion of said outer side wall being inclined inwardly toward said inner side wall and the upper portion of said outer side wall being substantially vertical and having a series of jet ports circumferentially spaced about the same, a gas inlet port opening through the bottom wall, and a vertically disposed baffle plate extending downwardly from the upper portion of said outer side wall to be horizontally opposite the lower portion of said outer side wall, said plate being longitudinally arcuate to extend partially about the circumference of the burner and having its lower edge disposed below the series of jet ports and facing the gas inlet port to divide the stream of inflowing gas and being of increasing depth from each end thereof to an intermediate portion and said intermediate portion of greatest depth being opposite the gas inlet port.

BEST PRATT.
